Primary Examiner — Jennifer Rivard*Assistant Examiner* — Jonathan E Fiencke(57) **CLAIM**

The ornamental design for a sink drain, as shown and described.

DESCRIPTION

FIG. 1 is a front and top perspective view of a sink drain showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is a bottom perspective view thereof.

The broken lines depict portions of the sink drain that form no part of the claimed design.

1 Claim, 8 Drawing Sheets(56)
